UNITED STATES PATENT OFFICE.

PHILLIP ASSNER, OF DORCHESTER, MASSACHUSETTS.

LOCKING DEVICE FOR BOX COVERS.

Application filed December 5, 1923. Serial No. 678,771.

To all whom it may concern:

Be it known that I, PHILLIP ASSNER, a citizen of the United States of America, and a resident of Dorchester, in the county of 5 Suffolk, in the State of Massachusetts, have invented certain new and useful Improvements in Locking Devices for Box Covers, of which the following is a specification.

This invention relates to devices for locking the covers of boxes provided with supplemental transparent covers to prevent access to the contents of a box while the latter is displayed upon a counter, said locking device being movable to unlock the cover when 15 it is desired to obtain access to the contents thereof.

The object of the invention is to provide means for preventing petty thefts of goods exposed upon a counter.

20 The invention consists in the production of a device which is extensible and adapted to fit various lengths of boxes and which may be quickly applied to a box, said device in one position locking the cover in a substantially 25 vertical position, while in another position said cover is unlocked and permitted to be moved rearwardly about its hinge connection with the box proper.

The invention further consists in certain 30 novel features of construction and arrangement of parts which will be understood readily by reference to the description of the drawings and to the claims to be herein-after given.

35 For the purpose of illustrating the invention, one preferred form thereof is illustrated in the drawings, this form having been found to give satisfactory and reliable results, although it is to be understood that 40 the various instrumentalities of which the invention consists can be variously arranged and organized, and the invention is not limited to the precise arrangement and organization 45 of the instrumentalities as herein shown and described, except as required by the scope of the appended claims. Of the drawings:

Figure 1 represents a horizontal section of a box with a device embodying the principles of the present invention applied thereto, said section being on line 1, 1, on Fig. 2.

50 Figure 2 represents a rear view of said box and the cover locking device.

Figure 3 represents a similar view with

the locking device in position to permit rear- 55 ward movement of the cover.

Figure 4 represents a vertical section of same on line 4, 4, on Figure 2, with the cover locked, and

Figure 5 represents a vertical section on 60 line 5, 5, on Fig. 2 with the cover unlocked and tilted back.

Similar characters indicate like parts throughout the several figures of the drawings. 65

In many stores it is the practice to expose certain goods for sale upon the counters where they are within reach of customers and this has led to petty thefts of some of the smaller articles, such as cigars, when 70 the salesman has been engaged in another part of the store.

To obviate this, some manufacturers of 75 cigars have provided the boxes with a transparent plate mounted in a metal frame having at its rear end a strap or bar on the front of the cover, this strap having slips at its opposite ends which enclose the ends of said cover. This plate permitted the cigars to be seen by the customer and at the same time 80 prevented dirt and other foreign substances entering the boxes and spoiling the same.

While such devices were obviously very desirable and possessed many advantages 85 there was nothing to prevent a person from lifting the transparent plate and removing some of the contents of the box when the salesman's back was turned.

These petty thefts have been so great that 90 it has been found necessary to provide some locking means to prevent the supplemental cover or plate being lifted except by the salesman. The device shown and described herein effectually accomplishes this purpose.

Referring to the drawings, 10 is a box 95 provided with a cover 11 hinged thereto at 12 in the usual manner.

On the front of this cover 11 is a strap 13 having at its opposite ends clips 14 which enclose the ends of the cover 11. This strap or bar 13 is formed integral with a frame 15 enclosing a glass plate 16 which is used to close the top of the box 10 when the main cover 11 is in open position and showing on its front face the name of maker and brand of the cigars exposed to view through the transparent plate 16. 105

These supplemental transparent covers

and means of attaching to the main cover of the box are usually provided by the cigar manufacturer and the present invention consists in providing a locking means which will coact therewith without changing in any manner the construction thereof.

The locking means consists of two plates 17-18, the former having a lateral extension 19 which is slidable in guides formed by inturned flanges 20, 21, formed upon the upper and lower edges of an extension 22 forming a part of the plate 18.

By sliding the members 17, 18, relatively to each other the device may be adjusted for use in connection with boxes of varying lengths.

There is enough friction between the extension 19 and the flanges 20, 21 to retain the members 17-18 in adjusted position.

20 The outer vertical edges of the members 17, 18, extend between the rear face of the cover 11 and the clips 14 and are freely slidable in a vertical direction.

The lower ends of the member 17, 18, are 25 provided with projections 23 which when the members 17, 18, are raised come into contact with the clips 14 to limit the upward movement of the locking device.

30 The flange 20 is provided with a rearward extension 24 by which the locking device may be lifted into the position shown in Figs. 3 and 5, to permit the plate 16 to be lifted to give access to the contents of the box 10.

35 This operation may be performed with one hand, the operator placing a thumb on the upper edge of the cover 11 and a finger on the under side of the extension 24 and moving thumb and finger toward each other until the projections 23 come into contact with the clips 14 and then without removing the hand the operator may move the cover 11 rearwardly about the hinge connection 12 and thereby lift the plate 16, thus permitting him to remove the contents of the box 100 with his other hand.

As soon as the purchase has been made both covers 11, 16, are returned to their normal positions as indicated in Fig. 4, and the 50 members 17-18 are returned to their lower positions with the ears 25 on the members 17, 18 extending upwardly above the hinge connection 12 and in contact with the rear face of the cover 11, thereby preventing further movement of said cover 11 until the members 17, 18 are again lifted.

It is obvious that the locking device is 60 hidden from the customers behind the box 10 and cover 11 and the customers are therefore in ignorance of what is locking the plate 16 to the box 10. This makes a very simple and inexpensive locking device for covers and it is believed that its operation and many advantages will be understood 65 without further description.

Having thus described my invention, I claim—

1. The combination with a box having a cover hinged thereto and a supplemental transparent plate mounted on said cover by a strap having oppositely disposed clips enclosing the ends of said cover, a device at the rear of said box slidable within said clips and projecting above the hinge connection between said box and cover when said device is in its lowest position.

2. The combination with a box having a cover hinged thereto and a supplemental transparent plate mounted on said cover by a strap having oppositely disposed clips enclosing the ends of said cover, a device at the rear of said box slidable within said clips and having portions projecting above the hinge connection between said box and cover when said device is in its lowest position; and stop members on the lower end of said device to contact with said clips and limit the upward movement of said device.

3. The combination with a box having a cover hinged thereto and a supplemental transparent plate mounted on said cover by a strap having oppositely disposed clips enclosing the ends of said cover, a device at the rear of said box slidable within said clips and having portions projecting above the hinge connection between said box and cover when said device is in its lowest position, said device being formed in two parts adjustable relative to each other to adapt it to various lengths of boxes.

4. The combination with a box having a cover hinged thereto and a supplemental transparent plate mounted on said cover by a strap having oppositely disposed clips enclosing the ends of said cover, a device at the rear of said box slidable within said clips and having portions projecting above the hinge connection between said box and cover when said device is in its lowest position, said device being formed in two parts, one of which is provided with inturned flanges forming guides for an extension on the other member.

5. The combination with a box having a cover hinged thereto and a supplemental transparent plate mounted on said cover by a strap having oppositely disposed clips enclosing the ends of said cover, a device at the rear of said box slidable within said clips and having portions projecting above the hinge connection between said box and cover when said device is in its lowest position, said device being formed in two parts, one of which is provided with inturned flanges forming guides for an extension on the other member, the upper flange having a rearwardly extending projection.

6. The combination with a box member having a cover member hinged thereto and provided with a transparent plate forming

a supplemental cover, a locking device slidably mounted on one of said members with projecting portions in the rear of the other member and adapted to be moved in a vertical direction into a position wholly behind the first mentioned member.

Signed by me at 746 Old South Building,

Boston, Massachusetts, this 3rd day of December, 1923.

PHILLIP ASSNER.
